United States Patent Office.

JAMES R. TAYLOR, OF NEW YORK, N. Y.

Letters Patent No. 60,963, dated January 1, 1867.

IMPROVED BOAT-DETACHING TACKLE.

The Schedule referred to in these Letters Patent and making part of the same.

TO ALL WHOM IT MAY CONCERN:

Be it known that I, JAMES R. TAYLOR, of the city, county, and State of New York, have invented certain new and useful improvements in Life-Boat Detaching Apparatus; and I do hereby declare the following to be a full, clear, and exact description of the same, reference being had to the accompanying drawings, making a part of this specification, in which—

Figure 1 represents a side sectional view of the apparatus, and its connection with the boat.

Figure 2 represents an edge view of the apparatus.

Figures 3, 4, and 5 represent a modification of the plan shown in figs. 1 and 2.

Similar letters of reference, where they occur in the separate figures, denote like parts in all the drawings.

In all boat-detaching apparatus of which I have knowledge, a block, hook, or other heavy weight is attached to the end of the rope, from which the boat is detached, and in letting the boat go, this block, hook, or other connecting device is apt to fly or swing around, with great danger to the operator or crew. The object of this invention is to detach from the end of a rope or ropes, without block, hook, or tackle, at the end of such rope or ropes, the rope being simply cat-tailed, plaited, or foxed, so as to clear nicely, and nor fray out. And my invention consists in giving the detaching rope or ropes a bite or half bite in the holding-head, and then clamping the end (or a point near the end) of the rope by an eccentric lever, to which the detaching or working apparatus is fixed.

To enable others skilled in the art to make and use my invention, I will proceed to describe the same by reference to the drawings.

A represents the holding-head, which is securely fastened to the keel B, or other part of the boat. In the top of the head are two cross-bars *a a*, which may be smooth and rigidly fixed, or one or both may have a sleeve or pulley upon them, which may be smooth or roughened, so that the rope may run more or less free through or between them, as may be desired. Below these bars *a a* there is arranged a swinging or pivoted eccentric-headed lever B', which may be grooved or roughened so as to hold hard against the rope, or the head of the lever may press against a roughened foot, B'', which is separate from the lever, as shown in fig. 1, both devices performing the same office in the same manner. The rope C, which is attached to the davit, is passed, first, between the two bars or rollers *a a*, thence between the under bar or roller and the roughened eccentric B' or the foot-piece B'', and when the free end of the lever is dropped, the eccentric portion gripes the end of the rope firmly. The two half turns of the rope at the upper and the lower bar or roller and the bite of the roughened eccentric will firmly hold the boat to the rope without any hook, link, block, or other tackle. To the free end or long arm of the lever B' is attached a line, *c*, which extends upwards or to the seat of the operator, and is secured to a draw key, *d*, so that the lever may be drawn up into the position shown in red lines in the drawings, which releases the cam or eccentric from its hold on the rope, and the latter is then free to run out from between the bars, and disconnect itself from the holding-head. To the long arm of the lever may also be connected a line, *e*, which may unite with a similar lever at the opposite end of the boat, that operates with a similar holding device at that end, so that both ends may be detached simultaneously, or as nearly so as practicable with safety. Or the line *e* may pass over a friction-pulley in the end of the key, and thence to the opposite lever, so that drawing on the key will first take up the slack and bring the strain upon both levers at the same time and detach simultaneously. The rope, instead of being a round one, may be a flat rope, braided or otherwise.

Having thus fully described my invention, what I claim therein as new, and desire to secure by Letters Patent, is—

Connecting and detaching a boat from the end of a rope by the combined use of the bars and cam or eccentric lever, and the end of the rope passed or reeved through or between them, substantially as described.

JAMES R. TAYLOR.
